[57] CLAIM

The ornamental design for a contact lens sterilizer unit, substantially as shown and described.

DESCRIPTION

FIG. 1 is a perspective view of our contact lens sterilizer unit design with the cover for the heating well in the closed position;

FIG. 2 is a top plan view of the sterilizer unit of FIG. 1; FIG. 3 is a front elevational view of our sterilizer unit design;

FIG. 4 is a rear elevational view of said sterilizer unit design;

FIG. 5 is a left side elevational view of the sterilizer unit in FIGS. 1-4; as viewed; and

FIG. 6 is a right side elevational view of the sterilizer unit as viewed.

FIG. 1.

FIG. 2.

FIG. 3.

FIG. 4.

FIG. 5.

FIG. 6.
